Primary Examiner — Marianne N Pandozzi*Assistant Examiner* — Jae Liang(74) *Attorney, Agent, or Firm* — Amin, Turocy & Watson, LLP(57) **CLAIM**

The ornamental design for a cup with shaped bottom, as shown and described.

DESCRIPTION

FIG. 1 is a top front perspective view of a cup with shaped bottom showing my new design;

FIG. 2 is a bottom-rear perspective view of the cup of FIG. 1;

FIG. 3 is a front view of the cup of FIG. 1;

FIG. 4 is a rear view of the cup of FIG. 1;

FIG. 5 is a right side view of the cup of FIG. 1;

FIG. 6 is a left side view of the cup of FIG. 1;

FIG. 7 is a top view of the cup of FIG. 1; and,

FIG. 8 is a bottom view of the cup of FIG. 1;
